UNITED STATES PATENT OFFICE

HYMEN A. BLANCHARD, OF BUFFALO, NEW YORK

BUILDING CONSTRUCTION

Application filed August 17, 1927. Serial No. 213,568.

This invention relates to improvements in building constructions and is more particularly directed to a combination of elements which may be assembled in situ and which 5 consists generally of supporting columns and frame bars and concrete slabs or equivalent wall elements whose assembly is maintained by the frame parts, the construction being especially available for, although not 10 limited to, small out-buildings such as garages and the like.

The principal object of the invention is to provide frame parts of novel form and 15 relation such that the supporting columns 15 may have all necessary stability without the use of the usual foundation and may also be quickly and easily set up, accurately alined and centered, and securely maintained against sagging or yielding.

20 A further object is to provide frame parts which may be composed of conventional rolled structural shapes and may, therefore, be produced and made ready for use at comparatively slight expense.

25 An embodiment of the invention is illustrated in the accompanying drawing wherein:

Figure 1 is a perspective view of the completed building with roof and door removed.

30 Figure 2 is a fragmentary detail view of the window frame construction.

Figure 3 is a fragmentary top plan view of the window frame.

Figure 4 is a horizontal section through a 35 front corner column.

Figure 5 is a perspective, partly in section showing details of construction at the rear corner and side supporting columns.

Figure 6 is a horizontal section through a 40 side supporting column with slabs in place.

Figure 7 is a horizontal section through a rear corner supporting column with slabs in place.

Figure 8 is a perspective view of an inside 45 corner.

Figure 9 is a perspective view of a slab.

Figure 10 is a top plan view of a slab.

Figure 11 is a fragmentary perspective of 50 the slab showing details of the top and side edges of the slab.

The frame of the building is composed of parts which may be made from standard rolled or structural shapes. The frame includes a number of vertical columns which maintain the assembly of the wall elements. 55 The construction shown embodies two front columns 1 and 2, two rear columns 3 and 4, and intermediate columns 5. The columns 1, 5, and 3 at one side of the building are formed to provide pairs of opposed channels in 60 which the wall elements are fitted; and the columns 2, 5, and 4 at the opposite side of the building and the columns 3, 5, and 4 at the rear end of the building are similarly formed for a like purpose. The columns 1 and 2 65 in the construction shown serve as parts of the door frame and are therefore not constructed to provide for the arrangement of wall elements between them.

The column 1 is composed of an angle iron 70 member 6 having attached, as by rivets or otherwise suitably, to the inner face of its front flange a second but smaller angle iron member 7 which in connection with the side of the first angle iron member provides a 75 vertical channel 8 facing rearward. The column 2 is similarly constructed. The column 3 consists of an angle iron member 9 having riveted or otherwise attached to the inner face of its rear flange a channel iron member 10, the channel of which faces laterally and the base of which in connection with the side flange of the member 9 provides a channel 11 facing forwardly. The column 4 is similarly constructed. 80

The columns 5 are each composed of two channel iron members 12 attached as by rivets back to back and providing channels which face the channels of the adjacent columns of the same wall. 85

Each of said columns has one end embedded and anchored in an individual pre-cast block 13 of concrete. In erecting the structure, a number of holes are dug in the ground and partially filled with a slush mixture of concrete. The concrete blocks 13 are then positioned in the holes after which the upwardly extending columns are alined and relatively centered by sill bars 14 which are preferably angle irons and are suitably attached, as by 100

bolt and nut fastenings, to the outer faces of the columns at a point where the angle irons will rest upon the concrete blocks. Three of these angle irons 14 are provided in the construction shown, one at each side and one at the rear. The frame work is then leveled by leveling the angle irons 14 which is accomplished by properly lifting or lowering the concrete blocks and suitably maintaining the desired position until the slush mixture has hardened or "set." The foundation holes may now be filled up with dirt or other suitable material which is tamped about the blocks 13. The frame is completed by 15 horizontal upper bars along its four sides and which are preferably angle irons, their vertical parts being attached to the outer faces of the columns. The front upper bar 15 has its horizontal part directed inward and may serve as a support for the door (not shown); for this purpose being provided with hanging irons 16. The side and rear upper bars 17 preferably have their horizontal parts directed outward. Their utility is to brace 20 the columns to one another and maintain their relative centering at their upper ends and also in combination with the bar 15 to provide a support for the roof. This may be of any suitable construction and its illustration 25 is deemed unnecessary. By supporting the roof upon members which project outward beyond the columns seepage of moisture or rain water into the building or between the wall elements is avoided. The horizontal part 30 of the front bar 15 is cut away at its ends to provide recesses 18 which align with the channels 8.

The walls of the building are completed by any suitable wall elements. Concrete 40 slabs 19 are preferably employed. These are formed with cut away portions 20 extending along their vertical edges so as to provide reduced terminal portions which fit closely in the opposing channels of adjacent columns, 45 the faces of the slabs being flush with the outer surfaces of such columns. The vertical edge faces of the slabs are also formed with longitudinal grooves 21 to provide clearances for the heads of the rivets or other fastenings by which the parts of the several columns are secured together. The diagonally 50 opposite horizontal edges of the slabs are cut away or rabbeted as at 22 so as to lap over one another in a manner known as "ship-lap" 55 and thus provide a water tight joint, the lower joint line being on the outer side of the building. In order to reinforce the building, the columns at the ends of the side walls and the rear wall are connected by tie rods 23 60 which extend through grooves 24 in the upper faces of the slabs and through apertures in the columns 5, the tie rod in the rear wall being offset one slab from the tie rods in the side walls. The lowermost slab 19 is supported by the blocks 13, resting upon the

upper faces of adjacent blocks and in this way each pair of blocks 13 provides support for a section of the wall.

A window frame may be provided in one of the walls of the building by substituting two short length slabs 19^a for two slabs of the standard length in one of the intermediate sections of such wall and utilizing the channel in the adjacent supporting column 5 as one side of the frame. The corresponding opposite vertical side of the frame is provided by two short length channel bars 25 secured back to back, whereby one channel fits over the slabs 19^a and the other channel is available for holding the window. The upper and lower window frame bars may be similarly constructed but are preferably provided by the backs of single channel irons 26, the channels of which fit over the adjacent slab.

It will of course be understood that the embodiment herein shown represents a building of the simplest form and that the features of the invention are applicable to buildings of varying and more elaborate design. It will also be understood that hollow walls may be used if desired, the provision for this variation consisting merely in making the channels of the columns of sufficient width to carry two series of slabs which may be separated from one another by wooden spacing blocks 95 secured to the bases of the channels.

Having fully described my invention, I claim:

1. In a concrete building structure a framework consisting of vertical columns, each having its lower end anchored in a pre-cast concrete block and formed with vertical structural channels to be arranged in opposing relation to the similar vertical channel of an adjacent column and horizontal sill bars 100 adapted for connection to said columns along the lines of wall extent and at corresponding points of their height thereby to brace said columns to one another and effect their alignment and relative centering in combination with wall elements for which said blocks provide support, the assembly of said wall elements being maintained by the opposing channels of adjacent columns, said blocks being adapted for alining adjustment in holes 105 in the ground severally provided therefor and for support on individual foundations in such holes.

2. In a concrete building structure a framework consisting of vertical columns, each having its lower end anchored in a pre-cast concrete block and formed with vertical channels to be arranged in opposing relation to the vertical channel of an adjacent column, horizontal sill bars adapted for connection to 120 said columns along the lines of wall extent and at corresponding points of their height thereby to brace said columns to one another and effect their alignment and relative centering, and horizontal roof supporting bars 125 se- 130

cured to said columns at their upper ends and along the lines of wall extent, in combination with wall elements for which said blocks provide support, the assembly of said wall elements being maintained by the opposing channels of adjacent columns, said blocks being adapted for alining adjustment in holes in the ground severally provided therefor and for support on individual foundations in such holes.

10 3. In a concrete building structure a framework consisting of vertical columns, each having its lower end anchored in a pre-cast concrete block and formed with vertical structural channels to be arranged in opposing relation to the similar vertical channels of an adjacent column and horizontal sill bars adapted for connection to said columns along the lines of wall extent and at points where 15 the bars engage all of said blocks, thereby to brace said columns to one another and effect their alinement and relative centering in combination with wall elements for which said blocks provide support, the assembly of said 20 wall elements being maintained by the opposing channels of adjacent columns, said blocks being adapted for alining adjustment in holes in the ground severally provided therefor and for support on individual foundations in such holes.

25 4. In a concrete building structure a framework consisting of vertical columns, each having its lower end anchored in a pre-cast concrete block and formed with vertical channels to be arranged in opposing relation to the vertical channel of an adjacent column, horizontal sill bars adapted for connection to said columns along the lines of wall extent and at corresponding points of their height 30 thereby to brace said columns to one another and effect their alinement and relative centering, and horizontal roof supporting bars secured to said columns at their upper ends and along the lines of wall extent, one of said 35 roof bars being provided with door hangers and cooperating with adjacent columns to form a doorway in combination with wall elements for which said blocks provide support, the assembly of said wall elements being 40 maintained by the opposing channels of adjacent columns, said blocks being adapted for alining adjustment in holes in the ground severally provided therefor and for support on individual foundations in such holes.

45 55 In testimony whereof I hereby affix my signature.

HYMEN A. BLANCHARD.
